UNITED STATES PATENT OFFICE.

JOHN Q. ADAMS, OF ALLEGHENY, PENNSYLVANIA.

DESIGN FOR A BLOCK FOR SCISSORS-SHARPENERS.

SPECIFICATION forming part of Design No. 25,714, dated June 30, 1896.

Application filed March 9, 1896. Serial No. 582,487. Term of patent 3½ years.

To all whom it may concern:

Be it known that I, JOHN Q. ADAMS, a citizen of the United States of America, residing at Allegheny, in the county of Allegheny and State of Pennsylvania, have invented a certain new and useful Design in Scissors-Sharpener, of which the following is a specification, reference being had therein to the accompanying drawings.

- 10 This invention relates to a new design for scissors-sharpener, of which the following is a specification, reference being had to the accompanying drawings, showing the same, in which—
- 15 Figure 1 is a perspective view of the block complete. Fig. 2 is an end view thereof. Fig. 3 is a rear elevation, and Fig. 4 is a view partly in section.

The leading feature of the design is an L-

shaped block A, having a rounded upper edge 20 B, the rear portion of the block being broken by a slot d, extending nearly to the bottom. The front face of the back a is broken by a slot d and by a diagonally-extending line D. The front of the base is molded as shown at G, and 25 the surface is broken by a recess E, as is clearly shown in Fig. 1.

Having fully described my invention, what I claim as new, and desire to secure by Letters Patent, is—

30 The design for a scissors-sharpener block, as shown herein and described.

In testimony whereof I affix my signature in presence of two witnesses.

JOHN Q. ADAMS.
